(57) **CLAIM**

The ornamental design for a display screen with an adjustable post-type support and circular base as shown and described.

DESCRIPTION

FIG. 1 is a top, front and right side perspective view of a display screen with an adjustable post-type support and circular base showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 in FIG. 2.

The even-dash broken lines shown in the drawings illustrate portions of the display screen with an adjustable post-type support and circular base, which form no part of the claimed design.

The dash-dot broken lines in FIGS. 2 and 9 represent the extents of the detail views and form no part of the claimed design.
